UNITED STATES PATENT OFFICE

WILHELM GLUUD AND KONRAD KELLER, OF DORTMUND-EVING, GERMANY

PROCESS OF PRODUCING FERRICYANIDES

No Drawing. Application filed June 5, 1928, Serial No. 283,120, and in Germany June 15, 1927.

Our invention refers to the production of ferricyanic acid and more especially to a method of producing this acid or its compounds from ferrocyanic acid or the compounds thereof.

5 Ferrocyanic acid and its compounds have already been oxidized in several ways, however, this oxidation was hitherto possible only with the aid of very powerful oxidizing agents, such as chlorine, lead peroxide and potassium permanganate.

10 We have now found as the result of many experiments that ferrocyanic acid and its compounds can be converted into ferricyanic acid and its compounds also with the aid of oxygen or gases containing oxygen, if the process is carried out in a certain manner.

15 We have found that if calcium ferrocyanide is exposed in watery solution under increased pressure and at moderate temperature to the action of air, it will be completely converted into calcium ferricyanide, according to the formula

As shown by this formula, the conversion results in an alkaline solution which exerts a destructive influence on the product of reaction. It is therefore necessary to add an acid, preferably a weak acid. If the gas containing oxygen, which is allowed to act on the calcium ferrocyanide, still contains carbon dioxide, no further addition of acid is required. We may, however, also add a weak acid, such as acetic acid or oxalic acid, to the solution from the beginning.

40 The oxidation can be effected with different kinds of gas mixtures containing oxygen, but also with pure oxygen. The well known processes for the production of ferrocyanic acid and its compounds from cyanogen and from cyanides may of course be combined with the process according to the present invention so that ferricyanic acid and its compounds can be produced in a continuous operation from cyanogen or from cyanides.

Example

50 A 5 per cent solution of potassium ferrocyanide (calculated for $\text{Ca}_2\text{Fe}(\text{CN})_6 \cdot (2\text{H}_2\text{O})$)

is treated in an autoclave at a temperature of 80-100° C. with compressed air containing 5 per cent carbonic acid, the operating pressure being 80-120 atms.

The following figures illustrate the course 55 of the oxidation in dependency from time.

Duration of test minutes	Tempera-ture in centi-grades	100 ccms. of the solution contained				Ferricya-nide calculated as ferro-cyanide grams	Oxidized ferro-cyanide per cent.		
		$\text{Ca}_2\text{Fe}(\text{CN})_6 \cdot (2\text{H}_2\text{O})$ (grams)		$\text{Ca}_3(\text{Fe}(\text{CN})_6)_2 \cdot (2\text{H}_2\text{O})$ (grams)					
		I	II	I	II				
0	0	20	20	6.8	7.0				
30	15	80	70	5.4	6.9	0.9	0.07		
60	30	100	100	0.4	1.73	4.7	3.9		
90	45	100	100	0.3	0.81	4.75	4.65		
	60		100	0.45		4.75	6.4		
							6425		
							93.5		

We are aware that the conditions of operation of this process may vary within wide limits and that the temperature and pressure as well as the starting materials may be varied greatly. The expressions "ferricyanide" and "ferrocyanide" used in the following 70 claims are intended to designate all compounds, including acids, bearing the ferricyanide or ferrocyanide radicle, respectively.

75 Various changes may be made in the details disclosed in the foregoing specification 80 without departing from the invention or sacrificing the advantages thereof.

We claim:

1. The process of converting a ferrocyanide to ferricyanide which comprises passing 85 a gas comprising free oxygen through a solution of the ferrocyanide under elevated pressure and temperature in the presence of acid.

2. The process of converting a ferrocyanide to ferricyanide which comprises passing 90 a gas comprising free oxygen through a solution of the ferrocyanide under elevated pressure and temperature in the presence of a weak acid.

95 3. The process of converting a ferrocyanide to ferricyanide which comprises passing a gas comprising free oxygen through a solution of the ferrocyanide under elevated pressure and temperature in the presence of carbonic acid.

4. The process of converting a ferrocyanide to ferricyanide which comprises passing a gas comprising free oxygen through a solution of the ferrocyanide under elevated pressure and temperature in the presence of acetic acid.

5. The process of converting a ferrocyanide to ferricyanide which comprises passing a gas comprising free oxygen through a solution of the ferrocyanide under elevated pressure and temperature in the presence of oxalic acid.

6. The process of converting a ferrocyanide to ferricyanide which comprises passing air containing carbon dioxide through a solution of the ferrocyanide under a pressure of from 80 to 120 atmospheres and at a temperature of from 80° to 100° centigrade.

In testimony whereof we affix our signatures.

WILHELM GLUUD.
KONRAD KELLER.

CERTIFICATE OF CORRECTION.

atent No. 1,872,929.

August 23, 1932.

WILHELM GLUUD ET AL.

It is hereby certified that error appears in the printed specification of the above numbered patent requiring correction as follows: Page 1, line 69, in the table, 10th column, for "6425" read 6.25; and that the said Letters Patent should be read with this correction therein that the same may conform to the record of the case in the Patent Office.

Signed and sealed this 18th day of October, A. D. 1932.

Seal)

**M. J. Moore,
Acting Commissioner of Patents.**
